Attorney,

UNITED STATES PATENT OFFICE.

CONRAD J. DORFF, OF CHICAGO, ILLINOIS.

ELECTRIC-WIRE SPLICER.

No. 891,825.

Specification of Letters Patent.

Patented June 30, 1908.

Application filed June 27, 1907. Serial No. 381,016.

To all whom it may concern:

Be it known that I, CONRAD J. DORFF, a citizen of the United States of America, and a resident of Chicago, in the county of Cook and State of Illinois, have invented certain new and useful Improvements in Electric-Wire Splicers, of which the following is a specification.

This invention relates to splicers for electric wires, and more especially to the type of splicers which constitute the subject matter of my prior patent No. 839,563, dated the 25th day of December 1906. And the present improvement has for its object to provide a simple and efficient structural formation of the splicer, which during the twisting operation of making a joint, maintains a true circular form of the wire receiving bores of the splicers and insures forcible and perfect gripping of the interior of such bores upon the entire peripheries of the wire ends embraced within the same, and a consequent cold welding of the surface in contact to afford perfect and continued electrical conductivity, all as will hereinafter more fully appear.

In the accompanying drawings:—Figure 1, is an elevation of the present splicer in an un-twisted condition ready to receive the wire ends. Fig. 2, is a similar view of the splicer in its twisted condition. Fig. 3, is an enlarged end wire view of the splicer. Figs. 4 and 5 are enlarged transverse sections of the splicer before and after the twisting operation.

Similar numerals of reference indicate like parts in the different views.

Referring to the drawings, 1 represents the body of the splicer, formed of a strip of ductile metal and having a rhomboidal form in cross section. In the present construction said strip or blank is bent along its length in opposite directions in the form of

the figure eight to form two adjoining circular channels 2 and 3, in parallel relation and adapted to receive the respective ends of the wire that are to be spliced. With the described construction the acute edges 4 and 5 of the strip or blank have extended abutment against opposite sides of the central part of the same, and provide a true circular cross-section to the channels 2 and 3, aforesaid, as illustrated in Figs. 3 and 4.

With the present construction, as the splicer is submitted to the usual twisting operation, the true circular form of the channels 2 and 3 is preserved, with a consequent intimate and forcible contact between the interior of the channels and the wire ends within the same, and with the aforesaid forcible contact of the surfaces tending to effect a cold welding of such surfaces and a permanent electrical conductivity of the splice, the operation just described being graphically illustrated in Figs. 4 and 5 of the drawing.

Having thus fully described my said invention what I claim as new and desire to secure by Letters Patent is:—

1. A wire connector formed of a strip of sheet metal two of whose opposite edges or sides are beveled and reversely bent to form parallel tubes adapted to receive the ends of the broken wire.

2. A splicer for electric wires formed of a flat blank rhomboidal in cross section and bent lengthwise into a figure eight form, with the acute ends of the blank bearing upon the middle portion of the blank at opposite sides thereof, for the purpose set forth,

Signed at Chicago, Illinois, this 25 day of June 1907.

CONRAD J. DORFF.
